Patented Feb. 26, 1918.

Fig. 1.

UNITED STATES PATENT OFFICE.

BERNARD P. SMITH, OF ST. LOUIS, MISSOURI.

BATH SPRAY-FIXTURE.

1,257,751.

Specification of Letters Patent. Patented Feb. 26, 1918.

Application filed April 9, 1917. Serial No. 160,664.

To all whom it may concern:

Be it known that I, BERNARD P. SMITH, a citizen of the United States, and resident of St. Louis, in the State of Missouri, have 5 invented certain new and useful Improvements in Bath Spray-Fixtures, of which the following is a specification, containing a full, clear, and exact description, references being had to the accompanying drawings, 10 forming a part hereof.

My invention relates to improvements in "bath spray fixtures," wherein a sprinkler head, is arranged for ready attachment to or detachment from mixing faucets, of varying sizes, as commonly employed on bath 15 tubs, and in which the perforations are arranged to discharge jets of water against the entire inner surface of the tub, and which head is provided with a deflector, serving 20 to confine the issuing water within the limits of the tub.

My object is to provide a bath spray fixture, for use in bath tubs, of simple, inexpensive and durable construction, and arranged for ready coupling with any ordinary mixing faucet and provided with means for confining its discharge within the 25 limits of the bath tub.

My improvements consist in the novel construction, arrangement and combination of parts as fully, clearly and concisely set forth in my specification, pointed out in my claim and illustrated by the accompanying drawings, in which—

35 Figure 1 is a longitudinal sectional elevation of a bath tub equipped with a fixture constructed according to my invention.

Fig. 2 is a plan of the fixture with a portion of the deflector broken away, and

40 Fig. 3 is a front elevation of the fixture, partly broken away and in section and showing it as coupled to a mixing faucet.

Referring to the drawings by numerals, 4 45 designates a bath tub and 5 a mixing faucet of the type having a detachable hose coupling 6, all of which in their specific constructions form no part of my invention and which may be of any of the well known constructions, shapes or styles.

50 In my drawings I show the discharge end of the mixing faucet provided with a conically ground seat 7 and internal threads 8 arranged to receive the hose coupling 6, having a conical head 9 and a stem 10, 55 which is held to the faucet by a sleeve nut

11, and it is to this stem 10 or its equivalent that I apply my improved fixture.

The fixture comprises a hollow body 12, preferably of a formation having greater capacity at its central portion and tapering 60 in each direction from its central portion.

In its lateral walls there are orifices 13 preferably extending throughout the entire lateral walls in order to direct jets of water in all directions against the walls of the bath 65 tub, and by preference the orifices in the forward central portion of the body are of greater capacity and in closer relative arrangement than the orifices in the remainder of the lateral walls in order, first, to direct 70 a greater volume of water, that is a number of jets of relatively large volume, forwardly in the central portion of the tub to play upon the body of a bather therein, and secondly, to direct jets of lesser volume to play 75 on the entire inner surface of the tub, thereby causing the water for the bath to heat the entire tub, preparatory to a bath and causing the spray to keep the entire inner surface of the tub cleansed.

80 Arising from the body 12 is a tubular stem 14, which is externally threaded at its upper end and arranged to receive thereover a sleeve nut 15, having at its top a lateral flange 16 and having wings 17 for ease of 85 manipulation.

Arranged between the end of the hollow stem 14 and the flange 16 of the winged sleeve nut 15 is a compressible gasket 18, centrally apertured to fit over the stem 10 of 90 the coupling member, and, having an annular groove 19 rendering it more readily conformable by compression to the stem 10 and adapting it for use to stems of different diametrical dimensions.

95 The orifices 13 are disposed to direct jets of water, within the limits of the tub, but in the event foreign matter should partially obstruct one or more of the orifices and change the course of the jet to cause it to 100 discharge outside the limits of the walls thereof, I have provided a deflector 20 which, as clearly shown in Fig. 1, stands in a position to confine the jets within the limits of the tub.

105 The device as a whole is applied to the mixing faucet by simply slipping the gasket over the stem of the coupling 6, then by turning the sleeve nut 15 compressing the gasket between the flange 16 and the end of the 110

tubular stem 14 to make a fluid tight and frictionally held joint between the gasket and stem 10.

Having thus described my invention, what I claim is:—

A spray attachment to bath tub faucets comprising means for attachment to a faucet, a chamber of small depth compared with its width and having its bottom wall directed 10 across the flow from the faucet, a perforated arcuate front wall having the perforations therein of different sizes, the perforations of greatest size being at the middle, thereby confining the entire spray substantially to 15 the shape of a bath tub, a perforated rear

wall for directing a washing spray over the wall of the tub adjacent the faucet, and a stationary deflector projecting beyond the chamber for confining the spray within the tub, the aforesaid combination constructed 20 for arrangement below the faucet to which it is attached.

In testimony whereof, I have signed my name to this specification, in presence of two subscribing witnesses.

BERNARD P. SMITH.
